(57) **CLAIM**

The ornamental design for a drilling and milling device, as shown and described.

DESCRIPTION

FIG. 1 is a perspective view of a drilling and milling device; FIG. 2 is a top view of the drilling and milling device of FIG. 1;

FIG. 3 is a bottom view of the drilling and milling device of FIG. 1;

FIG. 4 is side view of the drilling and milling device of FIG. 1;

FIG. 5 is another side view of the of the drilling and milling device of FIG. 1; and,

FIG. 6 is another perspective view of the drilling and milling device of FIG. 1.

In FIGS. 1–6, the broken lines and stippled features of the cutting edges and shank of the drilling and milling device depict unclaimed environmental subject matter and form no part of the design.
